FIG. 1

FIG. 2

FIG. 3

FIG. 1 is a top plan view of a laying cage house personnel carrier embodying my new design having a deck portion omitted.

FIG. 2 is a side elevation of the laying cage house personnel carrier shown in FIG. 1, the hidden side being the same as the visible side in FIG. 2.

FIG. 3 is an end elevation of the laying cage house personnel carrier shown in FIG. 1 and FIG. 2, the end opposite to that visible being the same as that shown in FIG. 3.

In FIG. 1 it is understood that the decking, shown with a portion broken away and omitted for convenience of illustration, is continuous over the area as indicated by FIG. 2 and FIG. 3.

I claim:

The ornamental design for laying cage house personnel carrier, as shown and described.
